UNITED STATES PATENT OFFICE

2,068,591

KITCHENETTE CABINET

Edgar L. Bennett, Chicago, Ill.

Application May 18, 1934, Serial No. 726,194

4 Claims. (Cl. 312—146)

This invention relates to cabinets and consists in a structure particularly adapted for use in small sized so-called efficiency apartments, summer homes, rooming houses, nurseries, etc., where 5 a single room frequently must serve a double purpose as kitchen and dining room, dining room and storage space, etc., although features of the invention are obviously not limited to this particular use.

10 An object of the invention is to provide a cabinet having storage space for dishes, food, etc., and also having a substantial refrigerating compartment which may be removed readily to facilitate access to the refrigerating mechanism.

15 Another object is to provide a cabinet door or panel structure contributing to the finished appearance of the cabinet but removable therefrom to be utilized as a table, preferably having folding legs for this purpose normally concealed 20 from view.

Another object is to provide a neat and attractive cabinet adapted to enclose and conceal all of the equipment ordinarily necessary in a small kitchen, such as a stove, a serving table, a refrigerator, a sink, and water faucets, dishes, and other utensils.

25 Preferably the cabinet consists of separable units each formed complete in itself and all assembled readily and interchangeable with other 30 units for different cabinet combinations and to facilitate handling in shipment, moving, etc.

These objects and others hereafter appearing are attained by the structure illustrated in the accompanying drawings in which—

35 Figure 1 is a front view of the novel cabinet.
Figure 2 is a rear view of the cabinet.

Figure 3 is a vertical section taken on the line 3—3 of Figure 2.

40 Figure 4 is a horizontal section through the body of the cabinet but showing all of the cabinet doors in the closed position.

Figure 5 is a disassembled view of the novel hinge structure.

45 Figure 6 is a front view of the cabinet showing the compartments open.

The cabinet includes a base section 1, upright compartment-forming sections 2 and 3 spaced from each other and mounted upon the base section, a pair of upper compartment-forming sections 4 and 5 mounted upon and overlying sections 2 and 3 and extending over the space between them. Sections 1, 2, 3, 4, and 5 form a framework defining a chamber for receiving a refrigerator compartment 6.

55 Preferably each of the sections is formed as an

individual unit and is assembled readily with the other sections and secured thereto by means of screws or bolts 9, 10 and 11. Refrigerator compartment 6 is formed as a separate unit and is movable into the chamber formed by the other 5 sections to be assembled with the latter, but preferably is not secured thereto.

The refrigerator compartment is closed at the front by an insulated door 52. When closed, this door is positioned substantially inwardly from the front face of the cabinet as defined by the front 10 walls of sections 1, 2, 3, 4, and 5, leaving a recess bounded by the adjacent portions of sections 1, 2, 3, 4, and 5. A table panel 16 with folding legs 36 fits neatly into this recess, concealing the door 15 of compartment 6 and its hardware, with elements typical of refrigerator construction, and forming a panel serving to unitize the cabinet design. The legs 36, when fully folded, fit into the recesses 16a in the inner wall of panel 16.

20 Preferably table 16 is hinged at one side to the adjacent side wall 29 of compartment 2. Each of the hinges 30 includes swiveling portions 31 and 32, the former of which is secured to the side wall 29 and the latter of which is in angular form including a slot 33 in its outer leg. Attached to the panel 16 adjacent its edge is a plate 34 mounting a swiveling pin 35 having an enlarged head adapted to be inserted in one position through the slot 33 and rotated ninety degrees to prevent 25 withdrawal thereof from the slot.

30 This arrangement enables the user to swing the table 16 as a door, for occasional access to the refrigerator compartment, or to detach the member 16 from the cabinet and use it as a table. 35 The arrangement provides convenient means for storing the table in an out-of-the-way position and covering the refrigerator door, thus adding to the sightliness of the cabinet. The outer surface of member 16 is decorated to conform with 40 the surface decoration of the remainder of the cabinet.

The entire fronts of compartment sections 2 and 3 comprise swinging doors 12 and 13 hinged to the outer walls of the sections. The tops of 45 sections 4 and 5 comprise doors 25 hinged to the rear walls of the sections to swing upwardly and rearwardly, and the fronts of sections 4 and 5 consist of panels 26 hinged to the front edges of doors 25. Stay-arms 27 will hold the doors 25 50 in upright position in which panels 26 will hang down. Lights 28 are mounted upon walls 25.

Compartment 4 is provided with an electrical outlet 18 and may be used for a small stove or other electrical unit. Slidable within the lower 55

part of compartment 4 is a board 18 which serves as a work table or bread board and also as a cover for the bread box 17 therebeneath. Compartment 3 has a metal lining, a portion of which is 5 depressed, as at 20, to form a sink projecting downwardly into compartment 3. Faucets 21 are mounted on the rear wall of compartment 3 and a drain pipe 22 extends from the bottom of sink depression 20 through the rear wall of compartment 3. Beneath the faucets 21 are ventilating 10 perforations 23 and at the other end of compartment 5 is an electrical outlet 24.

The space above the top shelf 14 in compartment 3 may be used for storing dish cloths, 15 brushes, soap, etc., and preferably is provided with an inner door 15 of perforated metal which closes the front of this storage chamber and the end of the sink. The bread box in compartment 2 has ventilating openings 44. Also on the rear 20 wall of compartment 2 is a hook 45 for carrying a folding chair 46. Hook 45 may be large enough to support a plurality of chairs 46 and/or one or more chairs may be similarly mounted on the rear wall of compartment 3. Holes in the rear 25 wall of compartment 4 are provided for water pipes 47 and drainage pipe 22. Secured to the rear walls of the top compartments 4 and 5 in line with the plugs 18 and 24 are the electrical connection boxes 50 and 51.

30 The refrigerator box 6 includes a storage compartment having the usual rack or shelf 37 and the evaporator or cooling unit 38. Above the storage part of the box 6 is a compartment 39 housing the compressor and other refrigerator 35 mechanism. Projecting from the back of the refrigerator box is the ventilator device 40 enclosed at the sides and top and open at the bottom for admitting air to the cooling mechanism on one side of the panel 41 and permitting ex- 40 pulsion of air on the other side of panel 41. Air spaces 48 and 49 are normally provided all around the refrigerator box when in position in the cabinet.

The refrigerator box 6 is movably mounted 45 within the center compartment upon bearing rods 42, which slidably engage the top of base section 1. Castors 43 are provided on the rear lower edge of box 6 beneath the ventilator for engaging the room floor to facilitate withdrawal of the 50 box rearwardly from the cabinet to permit inspection and repair of the compressor through the top of compartment 39 without necessitating disturbance of objects stored in the refrigerator or other parts of the cabinet. The legs of castors 55 43 abut the rear edge of base section 1 to limit the forward movement of the box 6 into the cabinet.

The novel cabinet is adapted to contain substantially all of the equipment and storage space 60 ordinarily necessary in a small kitchen and when all of the doors are closed the equipment is thoroughly concealed. The outer surfaces of the cabinet walls and the various doors will preferably be harmoniously decorated so that when all 65 of the doors are closed the cabinet will present an attractive appearance so as to be placed in a

living room or dining room without marring the appearance thereof. The back of the cabinet will preferably be placed against a wall so as to conceal the ventilator, electrical connections, and chairs mounted thereon. Where the cabinet is 5 connected with gas or water pipes, preventing movement of the cabinet as a whole, the castors 43 on the rear of the refrigerator box may be omitted and the box may then be withdrawn through the front of the cabinet for inspection 10 and repair of the refrigerator mechanism through the open top of compartment 39.

The built-up or sectional construction of the cabinet renders it flexible in that additional sections may be added or certain of the prescribed 15 sections varied without affecting the appearance of the cabinet as a single unit. All of the compartments may, however, be permanently built into the cabinet. Obviously the interiors of the various compartments may be arranged for different equipment as may be desired. The cabinet may be modified in these and other respects while retaining the various inventive features embodied therein, and the exclusive use of all such modifications as come within the scope of the 20 appended claims is contemplated.

I claim:

1. In a cabinet, a compartment open in front and back and having side, top and bottom members, and a self-contained, fully insulated refrigerator unit normally located in said compartment and having a door in register with the front edges of said opening and having storage space accessible through said door, said unit having a refrigerator mechanism chamber, one of said cabinet 35 members normally obstructing access to said chamber, said unit being separately removable from said compartment rearwardly of said opening to permit access to said chamber.

2. The combination of elements specified in 40 claim 1 in which said mechanism chamber is in the top part of said unit, the interior of said chamber being conveniently accessible only through the top of said unit.

3. The combination of elements specified in 45 claim 1 in which said compartment section side and top members constitute imperforate and stationary cabinet panels.

4. In a cabinet, a compartment having panels at the sides and bottom thereof, a self-contained 50 and separately movable refrigerator unit normally located in said compartment and having bearings engaging said bottom panel and the floor beyond one edge of said bottom panel, said unit having storage space accessible through the front 55 of said compartment and unit and a mechanism space accessible through the top of said unit and being slidably rearwardly of the cabinet from said compartment on said bearings to permit access to said mechanism space, and a removable 60 closure for the front of said compartment, said floor engaging bearing being positioned to engage said cabinet bottom wall to limit the movement of said unit into said compartment so as to leave space for said closure member. 65

EDGAR L. BENNETT.
